UNITED STATES PATENT OFFICE.

LOUIS RENAULT, OF BILLANCOURT, FRANCE.

CARBURATION DEVICE FOR INTERNAL-COMBUSTION ENGINES.

1,210,533.

Specification of Letters Patent. Patented Jan. 2, 1917.

Application filed July 21, 1913. Serial No. 780,332.

To all whom it may concern:

Be it known that I, LOUIS RENAULT, a citizen of the French Republic, residing at Billancourt, Department of the Seine, in France, have invented certain new and useful Improvements in Carburation Devices for Internal-Combustion Engines; and I do hereby declare the following to be a full, clear, and exact description of the invention, such as will enable others skilled in the art to which it appertains to make and use the same.

It is a well known fact that it is difficult to construct carbureters for internal combustion engines whose operation is as satisfactory for starting and for slow speeds as for high speeds of the engine. Carbureters with a single nozzle do not properly operate for both low and high speeds, so it has been proposed to construct carbureters with two nozzles, one of which serves for starting and for slow speeds, and the other for normal and high speeds. It is important for slow speeds to place the carbureter as near to the fuel inlet of the engine as possible, but if the carbureter is so placed, it is necessary to place the fuel reservoir at a relatively high point, so that fuel may be fed to the carbureter by gravity, or else to supply the fuel from the reservoir under pressure.

The present invention aims to provide a carbureting device which will not necessitate the positioning of the fuel reservoir at a relatively high point, and yet will permit the use of a low speed carbureter located at a relatively high point, to wit, near the fuel inlet of the engine. This is accomplished by providing a main carbureter serving for normal and high speeds, which is located, as usual, sufficiently low to avoid the use of a reservoir under pressure, and an auxiliary or low speed carbureter located at the upper part of the engine or near the fuel inlet of the engine, which auxiliary carbureter does not necessitate the use of a super-elevated fuel reservoir or a special fuel-supplying device.

The invention is illustrated in the accompanying drawing, in which:

Figure 1 is a diagrammatic view showing the carbureting device in side elevation; Fig. 2 is a sectional view taken through the low speed carbureter; and Fig. 3 is a diagrammatic view illustrating a modification in which the low speed carbureter is located

in the return pipe of the water cooling system.

The low speed carbureter is represented at 1, and, as will be seen from Fig. 1, is located at the upper part of the engine in the vicinity of the valves, and is supplied with fuel by a capillary tube 2 from a fuel reservoir. In Fig. 1, the low speed carbureter is mounted adjacent the return pipe of the water cooling system, and as the carbureter is thereby constantly heated, the mixture is quickly ignited and permits easy starting and excellent running of the engine at low speed.

The main carbureter is shown at 3 and is located at a sufficiently low point to permit the fuel to be supplied thereto from the fuel reservoir by gravity.

The supply of the carbureted air from the main carbureter to the engine may be controlled by any suitable means, such as the rod 4 acting on the throttle valve 5. It is also desirable to provide throttle mechanism for controlling the supply of carbureted air from the low speed carbureter to the engine. Such mechanism is represented at 9 and is preferably connected with the throttle valve 5 of the main carbureter by a connecting link 8. The same lever employed to actuate the throttle valve 5, therefore, also actuates the throttle valve 9.

As will be seen from Fig. 2, the low speed carbureter consists of a nozzle 10 and an air inlet 11. The air enters at 11, passes the nozzle 10, where it is carbureted, and is then supplied to the engine through pipe 6'. The supply of carbureted air to the engine from the low speed carbureter is controlled by the throttle valve 9, which, in the position shown in Fig. 2, cuts off communication between the engine and the carbureter.

Preferably, the throttle valve 9 is so constructed as to vary the degree of carburation of the air, as the valve is actuated. This may be accomplished by providing a portion *a*—*b* which conforms to the arc of a circle having its center at the axis of the valve. When the valve is first opened by turning the same in a clockwise direction, in Fig. 2, the part *a*—*b* causes the cross section of the opening at the entrance to the passage 6', to remain constant, during the first part of the movement of the valve. Adjacent the portion *a*—*b* of the valve is

2

a portion $b-c$, the radius of which gradually diminishes from b to c . As the valve is still further opened, this portion $b-c$ will cause the cross section of the opening 5 at the entrance of passage $6'$ to gradually increase. When the portion $a-b$ is controlling the passage of the carbureted air to the engine through $6'$, a portion $d-e$ of the valve, whose radius decreases from 10 d to e , is controlling the amount of ~~air~~ passing the nozzle 10. When the portion $b-c$ is controlling the supply of carbureted air to the engine, a corresponding portion $e-f$, at the opposite side of the valve, 15 is controlling the passage of the air past the nozzle 10. The portion $e-f$ conforms to the arc of a circle whose center is at the axis of the valve. From this construction, it will be seen that when the cross section 20 of the passage at the entrance to the pipe $6'$, remains constant, the cross section of the passage adjacent the nozzle 10 is gradually increasing, and when the valve is further moved and the cross section of the 25 passage at the entrance to the pipe $6'$ is gradually increasing, the cross section of the passage adjacent nozzle 10 remains constant. The throttling system is so arranged that when the valve 9 is moved through the 30 arc $a-c$ in an anti-clockwise direction to close the passage $6'$, the valve 5 of the main carbureter opens the passage in the main pipe 6.

If so desired, the low speed carbureter 35 may be located inside of the return pipe of the water cooling system, as shown in Fig. 3, in which position, it may be readily heated by the cooling water returning from the engine cylinders.

40 What I claim is:

1. The combination with a water-cooled internal combustion engine and one of the water-conducting pipes associated with the cooling system, of a main carbureter for 45 normal and high speeds, and a low speed carbureter supplied with fuel from the main carbureter and arranged to be heated by said water-conducting pipe.
2. A carbureting device for internal combustion engines, comprising a main carbureter

for normal and high speeds, a low speed carbureter located at a higher level than said main carbureter and adjacent the intake manifold, means for controlling the supply of carbureted air from each of the 55 carbureters to the engine, and connections between said means whereby both may be simultaneously actuated.

3. A carbureting device for internal combustion engines having a single fuel supply, comprising two separate carbureters one arranged below and the other above the fuel supply level, means for controlling the supply of carbureted air from each of the carbureters to the engine, and connections 65 between said means whereby both may be simultaneously actuated.

4. A carbureting device for internal combustion engines having a single fuel supply, comprising a main carbureter for normal and high speeds arranged below the fuel supply level, a low speed carbureter positioned above the fuel supply level, means to control the supply of carbureted air from the main carbureter to the engine, 70 means to control the supply of carbureted air from the low speed carbureter to the engine, said last-named means adapted to vary the degree of carburation of the air admitted to the low speed carbureter, and 75 connections between both of said means.

5. A carbureting device for internal combustion engines, comprising two separate carbureters, one arranged below and the other above the intake manifold, and a 80 common means for regulating both carbureters.

6. A carbureting device for internal combustion engines, comprising two separate carbureters, one arranged adjacent the intake manifold and in close proximity thereto, and the other substantially below said first-mentioned carbureter and a common means for regulating both carbureters.

In testimony whereof I affix my signature, in presence of two witnesses.

LOUIS RENAULT.
